UNITED STATES PATENT OFFICE

2,279,373

ELECTRIC SHAVER

Earle G. Hines, West Milford, N. J., assignor to
 General Theatres Equipment Corporation, New
 York, N. Y., a corporation of Delaware

Application October 16, 1937, Serial No. 169,369

4 Claims. (Cl. 30—43)

Various types of electric shavers have heretofore been patented but so far as I know none of these shavers has been provided with any means to insure the correct positioning of the shaver relative to the skin of the user. Objection is frequently made to such shavers on the ground that it takes a more or less prolonged use thereof to learn just how to hold the shaver so as to get the best results. One of the objects of this invention is to overcome such difficulties by providing a guide member integral with and attached to the motor housing so that when the user places the guide substantially flat against his skin the shaving implement operated by the motor in the housing will be correctly positioned so as to give the best possible shaving results. With such a guide it is unnecessary for the user to spend a prolonged period of time in learning how to use the shaver.

Another object of the invention is to provide a support for the guard or shell in which the rotary blade is mounted. This support not only supports the said guard but also protects the same in case the shaver should be inadvertently dropped. I have therefore provided on an electric shaver a combined guide and support for the guard in which the rotary blade is mounted, serving not only as a protection and as a support for the said guard but also serving as a means to insure the correct positioning of the electric shaver relative to the face of the user so that the best results will be obtained even though the user has had very little experience with the electric shaver.

These and other objects will appear in the detailed specification and claims which form a part hereof.

The invention may be the better understood by referring to the annexed drawing in which

Fig. 1 is a bottom plan view of the electric shaver;

Fig. 2 is a side elevational view thereof;

Fig. 3 is an enlarged side elevational view of the guard having the rotary blade therein, and showing the connection between the rotary blade and the driving shaft;

Fig. 4 is a perspective view similar to Fig. 3 but with the guard removed;

Fig. 5 is a cross-sectional view on the line 5—5 of Fig. 2 looking in the direction of the arrows; and

Fig. 6 is a cross-sectional view on the line 6—6 of Fig. 2 looking in the direction of the arrows.

In the patent of John M. Wall and Leonard 55

M. Thorn, 2,216,994, there is shown a rotary type electric shaver which operates on the same principle as that described in this application except that in the said patent there was no guide provided. As shown in this application a housing 10 encloses an electric motor the electric current being supplied through a cable 11. The motor drives a motor shaft 12 which is provided with pins 13 which project into a slot 14 forming a part of a rotary shaving member 15 and cutting blade 16. The rotary shaving member 15 rotates within a guard 17 which is provided with longitudinally extending grooves 18 and the housing is provided with tongues 19 which project into the said grooves 18 so as to hold the guard against rotation and to insure that the guard cannot be inserted into the housing except in a predetermined position. The guard is cut away at its sides as is clearly shown in Fig. 6 so as to form cutting edges 20 so that if the blades 16 rotate in a clockwise direction as viewed in Fig. 6 the blade will engage the hairs 21 and will cut the same. The guard 17 is also provided with slots 22 which extend circumferentially of the guard for a short distance thereby forming combs between the said slots which guide the hairs into the cutters. As above mentioned the guard 17 is cut away at its sides thereby forming a plane 23 which is tangential to the circle formed by the rotation of the periphery of the blades thereby forming a narrow slot 24 extending lengthwise of the guard and positioned between the cutting edges 20 and the teeth between the slots 22.

35 The best results are obtained by holding the implement so that the plane 23 will be flat against the surface of the skin of the user. In order to insure that the user will so hold the electric shaver, I have provided an extension of the housing forming a guide 25 having substantially flat surfaces 26. The object of the guide 25 is that if the user will place one of the opposite surfaces 26 against his face or the part to be shaved, the guard and rotary blade will be positioned so as to give the best results in shaving. The surfaces 26 need not be precisely flat for it is not absolutely essential that the shaver be held in a precise position but if the guide is so formed that it will insure the correct position of the guard and cutter it is obvious that the best results would be obtained.

40 It will be noted that the housing 10 is substantially oblong but is of such configuration as to nicely fit into the hand of the user. I prefer to make the guide 25 as an integral part of the

housing and to form a continuation thereof; but from the results to be obtained the guide might be made separate. Not only is the guide 25 a positioning means or indicator but it will be noted that the part 27 thereof which is immediately adjacent the guard forms the arc of a circle and the guard 17 rests against this arc of a circle formed by the guide so as to support the guard throughout the length of the guard. It is therefore apparent that the guard is nested against the guide and that in case the electric shaver should be inadvertently dropped on the floor in such a position that the guard first struck the floor the guide would support the guard and would protect it from material injury and from breaking the housing in which the guard was seated.

It is therefore apparent that the guide 25 when placed against the face of the user insures that the electric shaver is in the correct position to obtain the best results thereby eliminating a prolonged period of time in which the user must learn how to use the same.

While, broadly speaking, everything shown in the drawing and described in this specification might be considered as a shaving mechanism, I have used the expression "shaving mechanism" in the attached claims as referring to the rotary blade and guard; that is, in the claims where I have used the expression "shaving mechanism," I do not mean to include the housing and the motor carried by the housing, or the guide.

I realize that many changes may be made in the specific form or embodiment of the invention which is shown by way of illustration in this application, and I therefore reserve the right to make all changes or modifications relating to the same. I furthermore desire to claim the invention broadly except as I may limit myself in the appended claims.

Having now disclosed my invention, I claim:

1. In an electric shaver, an elongated housing, a guide member having side faces forming an extension of said housing, said side faces of said member being substantially parallel with the central plane through the width of said housing, a guard having a circular bore and having longi-

tudinally extending slots on opposite sides of said guard, the side of each of said slots forming a cutting edge, said cutting edges being in substantially the same planes as said faces and a rotary cutter in said bore adapted to cut whiskers between said cutter and edges.

2. In an electric shaver, an oblong housing, a guide provided with substantially flat faces forming a continuation of said housing, a guard provided with a longitudinally extending bore, said guard being carried by said housing and extending along said guide, said guard being provided with flat faces on its opposite sides forming planes tangential to said bore, said tangential planes being substantially continuations of the flat faces of the guide and a rotary cutter within said bore.

3. In an electric shaver, an oblong housing, a guide provided with substantially flat faces forming a continuation of said housing, a guard provided with a longitudinally extending bore, said guard being carried by said housing and extending along said guide, said guard being provided with flat faces on its opposite sides forming planes tangential to said bore, said tangential planes being substantially continuations of the flat faces of the guide and a rotary cutter within said bore, said guard being provided with a longitudinally extending narrow slot forming a cutting edge to coat with said cutter.

4. In an electric shaver, an oblong housing, a guide provided with substantially flat faces forming a continuation of said housing, a guard provided with a longitudinally extending bore, said guard being carried by said housing and extending along said guide, said guard being provided with flat faces on its opposite sides forming planes tangential to said bore, said tangential planes being substantially continuations of the flat faces of the guide and a rotary cutter within said bore, said guard being provided with a longitudinally extending narrow slot forming on one side of said slot a cutting edge to coat with said cutter, said guard being provided with a comb on the other side of said slot.

EARLE G. HINES.
